UNITED STATES PATENT OFFICE.

ARTHUR C. VAN HORN AND EDWIN E. BARNEY, OF GROTON, NEW YORK,
SAID BARNEY ASSIGNOR TO SAID VAN HORN.

DRAWING-BOARD.

SPECIFICATION forming part of Letters Patent No. 527,134, dated October 9, 1894.

Application filed April 20, 1893. Serial No. 471,167. (No model.)

To all whom it may concern:

Be it known that we, ARTHUR C. VAN HORN and EDWIN E. BARNEY, citizens of the United States of America, residing at Groton, in the county of Tompkins and State of New York, have invented certain new and useful Improvements in Drawing-Boards, of which the following is a specification, reference being had therein to the accompanying drawings.

10 Our invention relates to drawing boards and attachments; and it consists of a circular board pivotally connected with a suitable table or stand, and scales and mechanism by which angles and measurements may be

15 easily and accurately made.

In the accompanying drawings: Figure 1 is a top plan view of our improved board and stand. Fig. 2, is a vertical cross-section of the same; and Fig. 3, is a detail in side elevation, showing the mechanism for connecting the ruling blade with the thread of the leading screw.

Referring to the several parts by reference letters, A, indicates the top of a table or stand, 25 having an annular recess B' terminating centrally in an opening or socket. Into this recess is fitted a circular board B, which is provided with a central bearing or shank g that rests in the socket and forms a pivot 30 upon which the board may be rotated. Upon one edge of the board we form a semi-circular scale, which is divided into two quadrants of ninety degrees each, and in the table we pivot a latch f' which is intended to engage the board by means of notches or 35 holes formed upon its under side, so as to hold the board in whatever position it may be turned with reference to the ruling blade. It will thus be seen that lines can be drawn 40 upon the paper P at any desired angle.

The table A is provided with a rectangular frame, or one made to conform to its perimeter. This frame is provided upon one side with arms H H which form bearings for the 45 leading screw D. To this screw is attached the ruling blade E by means of the bow d' and sleeves D' D'. These sleeves are not threaded but move freely upon the screws as upon a smooth surface. Attached to one of 50 the sleeves is an arm a, to which is pivotally

secured an arm b at a'. The arm b has an opening d (see Fig. 3) which is provided with a half thread that meshes with screw D, the arm being normally held in engagement with the screw by means of a spring g'. When 55 it is necessary to move the blade E quickly across the board the operator presses the end of the arm marked b', which is more conveniently done by grasping the plate e' and the arm extension b' between the finger and 60 the thumb. This movement disengages the thread on the arm b from that on the screw D, and the blade E and connections can be moved rapidly from side to side of the board B. When however it is desired to move the 65 blade a short distance or to adjust it very accurately to the scale C', the hand wheel F is employed and the blade is advanced by the turning of the screw.

The wheel F is formed with a cylindrical 70 portion h upon which we mark divisions corresponding to those on the scale C'. This circular scale is employed when we determine the point to which the blade is to be moved by the eye of the operator. This gives greater 75 accuracy than can be had by looking at the ruling blade and C'.

Upon the shank of the screw D, we place a small wheel e, the periphery of which is divided into a series of faces upon which rests a spring f. This enables the operator 80 to determine by counting, the extent to which the scale has been advanced, and also serves to retain the screw in the position in which it is left.

The several scales may be divided in any proportion of measurement that may be found the most convenient.

From the above description it is believed 90 that any one skilled in the art can make and use our improved drawing board which we have endeavored to describe accurately and to claim specifically, but if by inadvertence, accident or mistake we have omitted to claim any part, parts or combinations, which we 95 might rightfully have claimed, we wish it understood that such omission or omissions are unintentional and nothing we have herein disclosed and that we could lawfully claim is abandoned to the public.

100

Having thus described our invention, what we claim as new, and desire to secure by Letters Patent, is—

1. A table or stand provided with a normally fixed scale upon its side, a board pivotally mounted upon the said stand, a ruling blade and positive means of attachment between the said stand and ruling blade for positioning said blade with reference to the scale, in the manner described and for the purpose specified.

2. A stand or table having an opening in its face, a circular board pivoted in said opening, one side of said board marking the degrees in a half circle, in combination with a fixed scale and a ruling blade secured to said stand at right angles thereto, and positive means of attachment between the said blade and stand to move the blade and position it at different points in relation to the said scale

on the stand and board, in the manner described and for the purpose specified.

3. The combination of the table having the fixed scale C, and the leading screw provided with the hand wheel and indexed portion h, ²⁵ with the ruling blade and means for engaging the blade with the thread of the screw, and to disengage it therefrom at will, substantially as set forth.

4. The combination of the leading screw D, the wheel e, and spring f with the wheel F, blade E and connections, substantially as set forth.

In testimony whereof we affix our signatures in presence of two witnesses.

ARTHUR C. VAN HORN.
EDWIN E. BARNEY.
